UNITED STATES PATENT OFFICE.

CHARLES M. GREISING AND JOHN DAHLIN, OF ST. PAUL, MINNESOTA, ASSIGNEES, BY
MESNE ASSIGNMENTS, TO INTERNATIONAL HARVESTER COMPANY OF NEW JERSEY,
A CORPORATION OF NEW JERSEY.

GUARD FOR BALLING-MACHINES.

1,237,635.

Specification of Letters Patent. Patented Aug. 21, 1917.

Application filed October 13, 1913. Serial No. 794,836.

To all whom it may concern:

Be it known that we, CHARLES M. GREISING and JOHN DAHLIN, citizens of the United States, and residents, respectively, of St. Paul, in the county of Ramsey and State of Minnesota, and of St. Paul, in the county of Ramsey and State of Minnesota, have invented certain new and useful Improvements in Guards for Balling-Machines, of which the following is a full, clear, and exact specification.

This invention relates to machines for putting twine into balls, and more particularly to safety devices for such machines.

After the fiber or material of which twine is made has been prepared and spun, the twine is made into balls on machines called "Balling machines." These machines have rapidly moving parts, such for instance as the flier, which revolves in a manner to feed twine onto a spindle to form balls.

In the operation of balling machines it is necessary that such machines be set into motion and stopped at frequent intervals, for the reason, among others, that a ball is formed in a relatively short time. It has been found by experience that operators have been injured in starting and stopping the operation of such machines, for the reason that their hands and arms have come into the path of the rapidly rotating flier. Again, many operators become careless and attempt to remove the formed balls from the spindle before the machine has come to a state of rest. Even though guards have been provided for the purpose of protecting operators from being injured by the rapidly rotating flier, in a great many instances operators have failed to make use of the guards, due to the fact that an extra operation was required to open and close the guard.

It, therefore, is primarily the object of this invention to render the operation of balling machines safer, and secondarily to control the operation of the machine and at the same time control automatically the operation of the flier guard to avoid injury.

These objects are accomplished by providing an interlock between the actuating mechanism of the balling machine and the flier guard in a manner that when the machine is set into operation the flier is completely covered by the guard, and the guard re-

mains in the protective position until the actuating mechanism of the machine has been rendered ineffective.

Our invention is illustrated on the accompanying sheets of drawings, in which—

Figure 1 is a side elevation of a balling machine embodying our invention;

Fig. 2 is a front elevation, parts being in section, of the same machine;

Fig. 3 is a side elevation of parts of the machine, including the interlock mechanism;

Fig. 4 is a front view of trip mechanism forming part of the interlock;

Fig. 5 is a side view of the same, taken from the opposite side shown in Fig. 3;

Fig. 6 is a detail view of a weighted bell crank lever forming a part of the interlock; and

Fig. 7 is a detail bottom view of a latch, forming a part of the same interlock.

The various novel features of our invention will be apparent from the description and drawings, and will be particularly pointed out in the appended claims.

This balling machine includes a main frame member 10, upon which is mounted a bracket 11, which supports a revolvably mounted bobbin 12 from which twine 13 is fed over a roller 14 and through a flier 15 onto a spindle 16, upon which a ball of twine 18 is formed by the rapidly revolving flier 15. The flier 15 receives its rotary motion from a shaft 17, upon which a sprocket 18 is mounted, said sprocket being in engagement with a chain 20 which passes over another gear mounted upon the flier spindle 19. The spindle 16 receives a relatively slow rotary movement from the same shaft 17 through a conical friction member 21 mounted upon said shaft and a friction wheel 22, mounted upon a shaft 23, having at one end thereof a bevel gear 24 in mesh with another bevel gear 25 which is associated with the spindle 16. Mounted upon one end of the main shaft 17 are a loose pulley 26 and a tight pulley 27, adapted to be engaged by a belt 28, which is shifted from one pulley to the other by a belt shifting bar 29, which is connected to a hand lever 30, said lever 30 being pivotally connected to the main frame 10 at 31.

From the above it is seen that by shifting the hand lever 30 the belt may be shifted

from one pulley to the other for starting and stopping the operation of the balling machine. Connected to the lower end of the lever 30 is a link 32, to which is connected a spring 33, the latter of which is connected to one end of a pawl 34, having a roller 35 adapted to engage notched portions of the bar 29 to hold the belt 28 in engagement with either one of the pulleys 10 and to prevent accidental shifting of said belt.

Heretofore guards which cover the flier, if used at all, have been operated by hand independently of the mechanism for controlling the operation of machine. For this reason, the guards were not consistently placed and maintained in a protective position when such machines were in operation. In other words, the guard may or may not 20 have been in a protective position when the machine was in operation, depending upon the attitude taken by the operator. To render it impossible for the guard to be in a non-protective position when the machine is 25 in operation, and to move the guard into a position to render the flier and spindle accessible only after the operating mechanism has been shut off or rendered non-effective, we have provided the following interlock between the guard and the actuating mechanism of the machine.

Pivoted to the lower end of the lever 30 is a link 38, having an elongated slot 39, which receives a pin 40 in a lever 41, the latter of which is pivoted at its lower end to a support 42 and connected at its upper end with a bar 42' connected with a flier guard 43. Bar 42' is provided with a notch 44, which is adapted to receive a latch 45 for normally holding the guard in a protective position over the flier when the machine is in operation. Latch 45 is mounted upon one end of a rod 47 journaled in a member 48. This member 48 and a corresponding one 49, both of which are secured to frame members 50, are provided with grooves 51, in which studs 52 of the guard 43 slide to direct the path of movement of said guard. As shown in Fig. 5, the latch 50 45 is provided with a projection 54 engaging a pin 55, which limits its movement in one direction. Secured to the opposite end of rod 47 is a trip member 56, having a weighted arm 57 and another arm 58 with 55 a laterally extending portion 59 lying in the path of movement of the controlling lever 30. As shown in Fig. 1, the latch 45 is held in the notch 44 under the influence of the weighted arm 57, said latch 45 thus holding 60 the guard in its normal protective position over the flier 15 against the tension of spring 60, one end of which is secured to the lever 41 and the other end of which is secured to a bracket 61 connected to the main frame 65 10. In order for the guard to move from

its normal protective position to a position rendering the flier 15 and spindle 16 accessible, it is necessary that the latch 45 be removed from the notch 44. This is done automatically when the operating lever 30 is moved from its normal full line position as shown in Fig. 1 to the dotted line position in the same figure. It is to be noted that as the lever 30 is swung from its full line position in Fig. 1 toward the dotted line 75 position in the same figure, the belt shifter 29 is moved to the left, shifting the belt from the tight pulley 27 to the loose pulley 26 without transmitting any motion whatever to the lever 41, due to the lost motion connection between link 38 and lever 41. By the time the operating lever has moved to a point where it engages the laterally extending arm 59 of lever 56, the belt 28 has been entirely shifted from the tight pulley 85 27 to loose pulley 26, thus rendering the actuating source or mechanism of the machine ineffective. A further movement of the operating lever 30 in the same direction causes said lever to force the latch 45 out of engagement with the notch 44, permitting the spring 60 to slide the guard 43 backwardly to render the flier 15 and spindle 16 accessible, as shown in Fig. 3. If it is desired to start the machine into operation again, the 95 operating lever 30 is shifted in the opposite direction, causing the guard 15 to move into a protective position through the connections 38, 41 and 42', at which time after said guard is in a protective position, the belt 28 100 is moved from the loose pulley to the tight pulley 27 for operating the machine.

From the above arrangement it is seen, therefore, that the balling machine can not be set into operation until the flier guard 43 105 is in a protective position, as shown in Fig. 1, and that said guard remains in such a protective position until the actuating mechanism of the machine has been rendered ineffective. It is further seen that this is 110 made possible by the interlock above described, and that the control of the guard is entirely automatic and is effected simultaneously with the control of the operating mechanism of the machine. 115

There may be various modifications of the precise form of our invention herein particularly shown and described, and it is our intention to cover all such modifications which do not involve a departure from the 120 spirit and scope of our invention as set forth in the following claims.

What we claim as new is:

1. In a balling machine, the combination of a flier guard, means for locking said guard in one of its positions, a member tending to move said guard into another position, means for starting and stopping the machine, and an operative connection between said guard and said starting and stopping 130

means, said guard being freed from said locking means to permit said member to move said guard into its other position when said starting and stopping means is operated.

2. In a balling machine, the combination of a flier guard, a member for locking said guard in a protective position, means tending to shift said guard into a non-protective position, and starting and stopping means for controlling the operation of the machine and the locking means permitting the guard to pass to a non-protective position.

3. In a machine having a moving part, a guard for said part, means for locking the guard in one of its positions, a member tending to move the guard into another position, means for controlling the operation of the machine, and an operative connection between said guard and said controlling means, said guard being freed from the locking means to permit the member to move the guard into its other position when the controlling means is operated.

4. In a balling machine, the combination of a flier guard, a member for locking said guard in one of its positions, a member tending to move said guard into another position, a lever for starting and stopping the machine, and an operative connection between the guard and lever, said guard being freed from the locking means to permit the member to move the guard into said other position when the lever is operated.

5. In a machine having a moving part, a guard for said part, a member for locking said guard in a protective position, means tending to shift the guard into a non-protective position, and control means for controlling the operation of the machine and the locking means permitting the guard to pass to a non-protective position.

6. In a machine having a moving part, a guard for said part, means for locking the guard in one position, means tending to shift the guard into another position, and control

means for controlling the operation of the machine and the locking means permitting the guard to pass from one of said positions to another position.

7. In a balling machine, the combination of flier guard, a lever operatively connected with said guard, a control lever, and a link extending between said levers, said link having a slot for the reception of a pin on one of said levers by means of which, when said control lever is moved in one direction, the lever is shifted to off position and then the guard is permitted to move away from its normal position.

8. In a balling machine, the combination of a flier guard, a lever operatively connected with said guard, a control lever, and a link extending between said levers, said link having a slot for the reception of a pin on one of said levers by means of which, when said control lever is moved in one direction, the lever is shifted to off position and then the guard is permitted to move away from its normal position, and when said control lever is moved in the opposite direction the guard is moved into its normal position and then the machine started into operation.

9. In a balling machine, the combination of a flier guard, means for locking said guard in its normal position, a lever operatively connected with said guard, a spring engaging said lever tending to move said guard away from its normal position, a control lever, and a lost motion connection between said levers, said control lever for controlling the operation of said machine and for actuating said locking member to permit said spring to move said guard away from its normal position.

In testimony whereof we affix our signatures, in the presence of two witnesses.

CHARLES M. GREISING.
JOHN DAHLIN.
